UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY, LIMITED, A COMPANY OF GREAT BRITAIN.

STEAM-TURBINE ESPECIALLY APPLICABLE TO THE PROPULSION OF MARINE VESSELS.

1,311,547.

Specification of Letters Patent. Patented July 29, 1919.

Application filed January 10, 1918. Serial No. 211,282.

To all whom it may concern:

Be it known that I, KARL BAUMANN, a citizen of the Confederation of Switzerland, and a resident of Urmston, in the county of 5 Lancaster, England, have invented a new and useful Improvement in Steam-Turbines Especially Applicable to the Propulsion of Marine Vessels, of which the following is a specification.

10. This invention relates to steam turbines and especially to turbines provided with both ahead and astern portions for the propulsion of marine vessels. In such turbines the most suitable construction in many cases 15 is that in which the ahead and astern elements are located on either side of the nozzle boxes from which the steam is respectively admitted to said elements. With such a construction a partition or diaphragm is necessary for separating the ahead from the 20 astern portion of the turbine.

The object of the present invention is to provide an improved construction of partition or diaphragm for separating the ahead 25 from the astern element of the turbine such that the nozzle boxes for the admission of steam to both the ahead and astern elements may be located in approximately the same plane perpendicular to the turbine shaft 30 whereby the overall length of the turbine may be reduced to the smallest limits.

A further object of the invention consists in so constructing the aforesaid partition or diaphragm that no portion thereof is subjected to steam at high pressure. 35

A typical constructional form of the invention is illustrated in the accompanying drawings in which Figure 1 is a central, longitudinal section of a marine turbine having 40 a partition or diaphragm for separating the ahead from the astern portion thereof constructed in accordance with this invention, Fig. 2 being a cross-sectional view taken on the line II-II of Fig. 1. Figs. 3 and 4 are 45 views similar to Figs. 1 and 2 illustrating a modification of the construction illustrated in Figs. 1 and 2.

Referring now to Figs. 1 and 2, the ahead portion of the turbine is illustrated at 5 and 50 the astern portion at 6. The partition or diaphragm separating the ahead from the astern portion comprises a tubular center

portion 7 surrounding the turbine shaft 8 provided with a labyrinth or other suitable packing 9 so as to reduce the leakage of 55 steam along the shaft from the ahead portion 5 to the astern portion 6, or vice versa.

At the ends of the tubular center portion 7 there are respectively located segmental diaphragms 10, 11, said diaphragms being 60 connected together by webs 12, 13, which extend from the central tubular portion 7 along the edges of the segmental diaphragms 10, 11, to the periphery thereof. The partition or diaphragm thus formed is held in 65 position in grooves 14, 15, formed in the cylinder wall.

The nozzle boxes for the admission of steam to the ahead portion of the turbine are shown at 16, 17, the single nozzle box for 70 admitting steam to the astern portion of the turbine being shown at 18. The nozzle boxes here illustrated are of the kind described in United States patent application, Serial No. 145,708, although nozzle boxes of 75 any other suitable type may be employed.

With a partition formed as above described and illustrated in Figs. 1 and 2 it will be seen that the nozzle boxes both for the ahead and astern portions of the turbine 80 may be mounted within the turbine cylinder in approximately a single plane perpendicular to the turbine axis, the nozzle boxes 16, 17 for the ahead portion being on one side and the nozzle box 18 for the astern portion 85 being on the other side of the partition or diaphragm, the latter completely shutting off the ahead from the astern portion of the turbine.

With this arrangement the nozzle boxes 90 are, when the turbine is in operation, surrounded by steam at comparatively low pressure and consequently by steam at a comparatively low temperature, particularly in the case of saturated steam. In order to 95 prevent excessive condensation or cooling of high pressure steam in front of the nozzles the nozzle boxes may be lagged with suitable insulating material.

Referring to Figs. 3 and 4, the partition or diaphragm is here provided with additional segmental diaphragms 19, 20, said diaphragms being supported in position in grooves 21, 22, formed in the free ends of the 100

tubular center portion 7. In order completely to separate the space surrounding the nozzle boxes from the remaining portions of the turbine additional division plates 23, 24, 5 25 may be provided supported in position, as shown, in grooves in the turbine cylinder. When such additional diaphragms and division plates are provided the steam surrounding the nozzle boxes will be super- 10 heated, but as no flow or windage of steam exists it will act as a heat insulator.

The partition or diaphragm above described is preferably formed separate from the turbine cylinder and is constructed in 15 two parts in a manner similar to the diaphragms carrying the stationary blading in a turbine of the impulse type. If desired, however, the partition or diaphragm may be made integral with the turbine cylinder.

20 The invention is not limited to the constructional form hereinabove described as this may be varied without departing from the spirit and scope of the invention. For example, the total number of nozzle boxes 25 used may be greater or less than three and the number of said nozzle boxes respectively used for the ahead and astern elements may be varied as may be found desirable, the position of the webs connecting the two 30 segmental portions of the diaphragm being correspondingly varied in accordance with the space needed for the accommodation re-

spectively of the ahead and the astern nozzle boxes.

I claim as my invention:

1. A steam turbine for the propulsion of marine vessels having both ahead and astern portions and a partition for separating the ahead from the astern portion comprising a central tubular portion surrounding the 40 shaft and at either end thereof a segmental diaphragm located in a plane perpendicular to the turbine axis, said segmental diaphragms being connected together by webs or the like extending from the central tubular portion along the edges of the segmental diaphragms to their periphery so that the nozzle boxes for the admission of steam to both the ahead and astern portions may be located in approximately a single plane perpendicular to the turbine axis. 45

2. A marine steam turbine having a partition for separating the ahead from the astern portions as claimed in claim 1, provided with additional segmental diaphragms 50 formed on the free ends of the central tubular portion so as to separate the space surrounding the nozzle boxes from the remaining portion of the turbine. 55

In testimony whereof, I have hereunto 60 subscribed my name this 23rd day of November, 1917.

KARL BAUMANN.
